Charles Edward Jones, ^{inventors,}

By their Attorneys F. Wright & Sons

UNITED STATES PATENT OFFICE.

THEODORE C. HAILES AND CHARLES EDWARD JONES, OF ALBANY, NEW YORK.

BOOK-COVER PROTECTOR.

1,183,972.

Specification of Letters Patent. Patented May 23, 1916.

Application filed April 13, 1915. Serial No. 21,075.

To all whom it may concern:

Be it known that we, THEODORE C. HAILES and CHARLES EDWARD JONES, citizens of the United States, both residing in the city and county of Albany and State of New York, have invented certain new and useful Improvements in Book-Cover Protectors, of which the following is a full and clear specification.

10 In the majority of the public schools of the country, books for the students are supplied by the school board, and to increase the life of the books as well as provide for sanitary requirements, it is the practice to 15 cover all school books with a paper protector or outer cover. This work of covering the books is frequently done by the students, either at school or at home, with the result that a good deal of the students' time is 20 consumed and the resulting covered books are far from uniform. The covering of the books is particularly necessary because they are transferred to different students a number of times, depending upon the life of the 25 books.

The purpose of the present invention is to provide a bound book with a cover protector that will avoid the necessity of using a home-made cover protector and which will 30 lend uniformity to the appearance of the school books and increase the length of service.

In its simplest form the improved book cover protector comprises a protector sheet 35 permanently attached at one or more points to the book cover and provided with means for facilitating its removal when it becomes worn or soiled.

40 In its more practical and useful form, the invention includes such a book cover protector formed of a plurality of superimposed sheets of proper material permanently attached to the cover at one or more points and completely inclosing the cover.

45 The means for facilitating the removal of the protector from the book cover comprise weakened lines or portions of the protecting material by which the material can be neatly torn away and removed from the 50 book cover. Any suitable device may be employed for this purpose including scored lines or perforations and wherever such expressions as "scored line," "perforations," "separating lines" and the like are employed

in the claims, such term is intended to indicate any device of this character which is intended to confine the tearing action to a predetermined line extending between a major portion which is to be removed from the book and a minor portion from which 55 said major portion is removed. In the form embodying a plurality of cover protector sheets, it is preferred to have the weakened lines or zones of the sheets out of register with each other, so as to avoid the danger of 60 removing more than one protector sheet at a time. It has been found desirable to also provide each of the plurality of protector sheets with a perforation into which a sharp instrument can be inserted for starting the 70 tearing of the protector sheet from the cover, and in case of using these starting openings it is preferred that the openings of the several sheets be placed out of register with each other. 75

Any suitable material such as paper or cloth may be employed in making the improved book cover protector, and if desired, the material may be chemically treated to render it germ-proof. 80

In order that our invention may be fully understood we will first describe the same with reference to the accompanying drawings, and afterward point out the novelty more particularly in the annexed claims. 85

In said drawing,—Figure 1 is a perspective view of a book provided with the improved book cover protector showing the outer protector sheet partially torn away to expose the next inner protector sheet. Fig. 90 2 is a perspective view of the book with one of the covers raised to show the arrangement of the cover protectors on the inner face of the book cover.

In the drawings, X is an ordinary bound book with stiff covers hinged to the back in the usual way. In binding such books the common practice is to provide the sewed book of leaves with strengthened cover-attaching sheets or fly leaves which are glued 100 to the previously prepared cover for securing the book in the cover. 95

In preparing a bound book with the improved cover protector, we propose to mount one or a number of protector sheets upon 105 the previously prepared book cover in such manner that the fly leaf of the book will be glued to the inside of the book cover after

the protector is in place. In accomplishing this the protector is permanently secured upon the book at one or more points without interfering with the removability of the 5 main body of the protector when it becomes worn or soiled.

In producing the cover protector, suitably blanked out sheets of proper material are prepared with weakened lines formed by 10 scoring or perforating, these weakened lines being located with proper regard to their desired position with reference to the book cover when the protector is folded and secured thereon.

15 The drawing illustrates a cover protector made up of two superimposed sheets or layers A and B. The inner layer A has its side and end edges $a-a'$ folded inwardly upon the book cover and secured thereon by 20 gluing in the usual way. This inner protector member is formed with lines of perforations 1, 2 and 3, shown in dotted lines in Fig. 2 of the drawing. This inner protector also has a perforation 5 in its outer 25 face for the reception of a pointed instrument to be used for removing the cover protectors. The title of the book may be printed on this inner cover protector as indicated in Fig. 1.

30 The second or outer protector B has its edges $b-b'$ folded inwardly upon the in-folded edges of the first protector sheet to which said edges are secured. This outer protector sheet has lines of perforations indicated at 6, 7 and 8, which lines are out of coincidence with the lines of perforations of the inner protector sheet. The outer protector sheet has upon its face a perforation indicated at 10 for the insertion of a sharp 40 pointed instrument. Each of the cover protectors therefore comprises a major cover portion and an attaching portion, the former being separable from the latter along a separating line extending between said portions.

45 When the plurality of cover protectors are properly folded upon and secured to the book cover in the manner explained, the book is bound into the protected cover in the usual manner, the reinforced binding sheets 50 or fly leaves of the book being glued over the inner surfaces of the book covers and portions of the inturned edges of the cover protectors, care being taken in securing the book in the protective cover that the binding fly 55 leaves α do not extend over the lines of perforations 1, 2, 3 and 6, 7, 8. A broken away portion of one of said binding leaves is shown at α in Fig. 2.

60 After the outer cover protector has become soiled or worn it can be removed by inserting a pointed instrument in the tearing hole or perforation 10, and tearing or cutting the protector sheet from the book. The weakened lines 6, 7 8 of this outer protector sheet serve to define the tearing lines

within the edges of the book cover, so as to insure a neat result to the removing operation. In Fig. 2 the outer protector sheet is shown partly removed from the book. When the outer protector is removed, the book will 70 have the next inner protector sheet presented to form an entirely new and clean cover protector.

75 While we have shown an improved book cover protector consisting of only two superimposed sheets, it will be clear that any practical number of such protector sheets can be employed. The number desired depending largely upon the length of life of the book from other standpoints.

80 We claim:

1. A bound book having a cover protector comprising a major portion extending over the outside surface of the book cover, and a minor portion attached to the inside surface of the book cover, said protector having scored separating lines extending between said portions to facilitate the removal of the major portion of said protector.

85 2. A bound book having a plurality of superimposed cover protectors arranged over the outside surface and portions of the inside surface of the book cover, each of said cover protectors being provided with a scored line extending between portions of the cover protector for facilitating the removal of one of said cover protector portions independently of the other.

90 3. A bound book having a plurality of superimposed separately removable cover protectors inclosing the book cover, and each formed with separating lines to facilitate their separate removal, said separating lines of the respective protectors being out 95 of register with each other.

100 4. A bound book having a cover protector inclosing the cover of said book, said cover protector being provided with means for confining a rupture of the material thereof to a predetermined path extending between major and minor portions of the cover protector, said minor portion being permanently attached to the cover.

105 5. The combination with a bound book, of a plurality of superimposed cover protectors each provided with a portion secured between the inside of the cover and a fly leaf pasted thereto, said cover protectors being provided with means adapting other portions covering the outer surface of the book cover 110 to be readily detached, each of said cover protectors being provided with a perforation for the insertion of a pointed instrument.

115 6. The combination with a book provided 120 with a cover and a binding sheet secured to said cover, of a cover protector having a portion thereof secured to the cover between said cover and binding sheet.

125 7. The combination with a book having a 130

cover, of a plurality of cover protectors, each comprising a minor portion and a major portion separable from said minor portion, said minor portions being secured 5 to the book between said book and cover.

8. The combination with a bound book, of a cover protector comprising a minor portion permanently attached to the cover of said book and a major portion extending 10 over the outer surface of said book cover, said protector being provided with weakened lines extending intermediately of said portions to facilitate the removal of the major portion of the protector.

15 9. The combination with a bound book, of a cover protector permanently attached to and inclosing the cover and formed with separating lines, said protector being provided

with a perforation for the insertion of a pointed instrument.

10. The combination with a bound book, of a plurality of superimposed cover protectors each provided with a portion secured 20 between the inside of the cover and a fly leaf pasted thereto, said cover protectors 25 being provided with means adapting other portions covering the outer surface of the book cover to be readily detached, each of said cover protectors being provided with a perforation for the insertion of a pointed instrument, said perforations of the respective protectors being out of register with each other.
